UNITED STATES PATENT OFFICE.

GUNERIUS SCHOU, OF CHRISTIANIA, NORWAY.

MAGAZINE BOLT-GUN.

SPECIFICATION forming part of Letters Patent No. 604,423, dated May 24, 1898.

Application filed April 28, 1897. Serial No. 633,908. (No model.) Patented in Norway June 6, 1896, No. 4,613, and October 10, 1896, No. 4,817.

To all whom it may concern:

Be it known that I, GUNERIUS SCHOU, a subject of the King of Norway and Sweden, residing at Christiania, Norway, have invented certain new and useful Improvements in Magazine Bolt-Guns, (for which I have obtained patents in Norway, June 6, 1896, No. 4,613, and October 10, 1896, No. 4,817;) and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in firearms; and the objects of my invention are, first, to simplify a rifle or similar gun, so that its working parts shall be very few in number; second, to so construct the working parts of a rifle or gun that they may be taken apart for cleaning and repair and put together again without tools, both of which points are obviously of great advantage both in the manufacture and the use of the gun; third, to provide a gun in which all the working parts are very durable and reliable and not apt to get out of order; fourth, to provide a gun in which the magazine may be filled with cartridges almost in an instant by simply dropping them in, without the resistance of springs, as is usually the case in guns heretofore used; fifth, to so simplify the mechanism of a gun that any ordinary person may readily understand to use it as well as to take it apart for cleaning, &c. These and other objects I attain by the novel construction and arrangement of parts illustrated in the accompanying drawings, in which—

Figure 1 is a left side view of the portion of a gun embodying my improvements. Fig. 2 is a top or plan view of Fig. 1 with the stock or woodwork omitted. Fig. 3 is a right side view of Fig. 2 with the arm 42 cut off at d d. Fig. 4 is an enlarged partly-sectional top view, as on the line e e in Fig. 3, with the working parts removed. Fig. 5 is a bottom view, and Fig. 6 a front end view, of the hammer-lifter. Fig. 7 is a sectional top view in the left side of the gun, about as on the line f f in Fig. 1.

Fig. 8 is an enlarged substantially central longitudinal vertical section of the gun with the breech-bolt pulled back. The trigger-spring, mainspring, stirrup, and ejector are 55 for clearness sake not shown in section. The following figures, except Fig. 12, are all enlarged to the same scale as Figs. 4, 5, and 8. Fig. 9 is a transverse section of the complete gun, shown as on the line a a in Fig. 8. Fig. 10 is a transverse section on the line b b in Fig. 8, but with all the working parts omitted. Fig. 11 is a transverse section on the line c c in Fig. 8 with all working parts omitted except the cartridge cut-off. All of said views, Figs. 65 9, 10, and 11, are shown as looking from the rear toward the front end of the gun. Fig. 12 is a detail bottom view of the cover or lid of the magazine and the cartridge-carrier and its spring. Fig. 13 is a side view, and Fig. 70 14 a top view, of the ejector. Fig. 15 is a side view, and Fig. 16 a top view, of the spring by which the cartridge-carrier is pressed against the side of the cartridges. Figs. 17 and 18 are detail views of the cartridge cut-off. Fig. 19 is 75 a rear end view, Fig. 20 is a side view, and Fig. 21 a front end view, of the breech-bolt. Fig. 22 is a side view, and Fig. 23 a front end view, of the firing-pin. Fig. 24 is a longitudinal sectional view of the breech-bolt about as on the line h h in Fig. 19, looking from right to left, and with the firing-pin inserted and the cartridge-extractor in its place. Fig. 25 is a front end view, and Fig. 26 a side view, of the extractor. Fig. 27 is a sectional view on the 80 line g g in Fig. 26, looking from left to right. Fig. 28 is a bottom view of Fig. 26.

Referring to the various parts in the drawings by reference-numerals, 1 designates the stock or woodwork of the gun.

2 is the barrel, which is screw-threaded at 3 into the front end of a metallic body or frame 3 4 5, of which the upper portion forms the receiver, the lower portion the magazine, and the rear portion houses the hammer and other working parts. The magazine for the cartridges is the annular chamber 7, extending between one-half and three-fourths of a circle around the receiver, and has its front and rear ends terminated by the annular walls 95 8 and 9, projecting transversely out from the outer curved wall 10 of receiver 4. (Best

shown in Figs. 8, 9, and 10.) The curved bottom 11 and left side wall 12 of the magazine are made integral and secured in place by the insertion of the ends 13 of the portion 12 upward into the straight grooves 14 in the left extremities of said end walls 8 and 9 and by the stock 1 below it. The right side of the magazine is provided with an opening 15, which may be closed or opened, so as to receive the cartridges sidewise into the magazine by moving up or down the curved lid 16, which slides with its ends in the curved grooves 17 in said end walls of the magazine.

18 is an out and upwardly projecting edge of the lid by which it is operated. In Fig. 9 is shown in dotted line 18^X the position of the lid while the magazine is being filled.

19 is the opening through which the cartridges enter from the magazine into the interior cylindrical space 20 of the receiver in front of the breech-bolt 21, which will presently be fully described. Upon a downwardly-projecting stud 22 swings pivotally the arm 23, which extends through the slot 24 in the wall 9 into the magazine, where it is provided with a downwardly-projecting arm 25 and a long limber upwardly-curved spring-arm 26, with a head 95 secured on its end. This arm is the cartridge-carrier, which tends at all times to move the cartridges upward into the receiver and is therefore also urged sidewise by being swung on its pivot 22 by the L-shaped carrier-spring 27^X, inserted with its offset end in the side cover 12, as shown at 28 in Figs. 1 and 7, and presses with its L-shaped end 29 against the side of the carrier.

The magazine-lid 16 is provided in its lower front corner with two notches 30 and 31, (see Figs. 7, 8, and 12,) of which the notch 30 is a clearing to allow the tooth 25 of the carrier to swing from side to side. The other notch 31 engages by its rear shoulder the said tooth 25, as shown in Fig. 12, and thereby positively locks the carrier, which, being spring-pressed, assists in holding by frictional contact the lid in the open position 18^X in Fig. 9, with the head of the carrier standing back, as to the left in the view, into the cavity 32 in the side lid 12, as shown in dotted line in Fig. 9, thus leaving the magazine open and unobstructed, so that all the cartridges it will hold can be dropped sidewise down into it in a moment, and as the lid is touched upward again it closes and the gun is ready for firing.

55 The cartridge cut-off (best shown in Fig. 18 and in the front end view, Fig. 17) consists of a small rock-shaft 33, provided near its middle with the thumb-catch or arm 34. The front end of this shaft is cut away, forming a half-round 35, which will alternately present its round or flat side to the cartridges, and thus will either prevent them from or allow them to enter the receiver, according to how the shaft is turned by the catch 34. The front portion 35 of the shaft is inserted in a hole 36 in the upper wall of the receiver, so that it may present its round side to the cartridge

when in the position 36^X, as shown in Fig. 9. The rear end of the shaft is journaled in a lip or projection 37, formed upon the rear end of 70 the receiver and provided with the notch or gap 38 for the arm 34 to pass through in extracting and inserting the shaft. In the lower side of the rear half of said rock-shaft is inserted and secured a spring-arm 39, of which 75 the downwardly-curved front end 40 engages the transverse groove 41 and, by frictional contact, holds the shaft in the desired position, as well as prevents its accidental withdrawal.

80 The breech-bolt 21, provided with the operating-arm 42, is in its lower side provided with a longitudinal groove 43, closed at its front end and having its rear end broadened into a wide notch 44. The ejector 45 (best shown in Figs. 8, 13, and 14) is a small two-armed lever pivoted in a short groove 46 in the bottom of the receiver. (See Fig. 8.) Its short end projects upward into the groove 43 of the breech-bolt and allows the long front 90 end to sink down into groove 46; but when the breech-bolt is pulled back to its full limit the solid front terminus 42^X of the groove 43 depresses the short end of the lever, causing thereby its front end to knock the empty cartridge upward and out of the receiver, and when the breech-bolt is pushed forward and turned to the right, so as to cause its locking-lugs 47 and 48 to enter the locking notches or cavities 49 and 50 in the upper wall of the receiver and the arm 42 to enter the notch 43^X in the side of the receiver, the ejector occupies the wide portion 44 in the under side of the breech-bolt. Between the cheek-plates 51 of the frame I mount on the two plain pivots 52 53 the hammer 54 and the trigger 55. The mainspring 56 (best shown in Fig. 8) is connected with the hammer by the stirrup 57 and is further held in place by the cheeks 51 and the notch 58 in the rear end wall of the frame. 59 is the trigger-spring, which is secured with its upper end to the rear tang 6 of the frame and presses with its lower end forward against the trigger.

105 The breech-bolt 21 houses in its round central opening 61 the firing-pin 62, of which the front end 63 is reduced, as usual, and its main body is round, while its rear end 64 is four-cornered as far as to the rigid collar 65, with which the pin is provided. This collar 110 is housed in a cylindrical cavity 66, formed in the reduced end 67 of the breech-bolt, which projects rearwardly beyond the operating-lever 42. The bottom of said cavity 66 and the front side of the collar 65 are both provided 115 with cams, as 68, which when meeting the tops of one another keep the firing-pin retracted, so it cannot touch the cartridge; but if the breech-bolt is turned so that its cams 68 register with the spaces between the cams 120 on the firing-pin the latter is at liberty to be thrown forward by the blow of the hammer upon its rear end and will then operate on the cartridge. The necessary turning of the

breech-bolt for said purpose takes place every time the breech-bolt is rocked about one-eighth of a turn to the right to interlock it in the receiver and back, so as to allow its retraction. The firing-pin is prevented from rocking or turning by having its square end inserted in the square hole 69 in the rear end portion 70 of the cartridge-extractor 71, which portion is provided with the cylindrical cavity 72, fitting upon the projection 67 of the breech-bolt. The tongue 73 of the extractor engages the annular groove or recess 74 at the base of the operating-lever 42. (Best shown in Figs. 21 and 24.) The front end of the extractor-bar 71 is brought down to the side of the front end of the breech-bolt, which it projects slightly beyond and is formed into the hook 75, adapted to take hold in an annular groove near the rear end of the cartridge and extract it from the barrel after it is fired. Upon the right side of the extractor-bar, near its front end, is provided the stop 76, which when the breech-bolt is pulled back catches against the rear terminus of the notch 50 in the upper part of the receiver. This notch is shown in Fig. 8, and in Fig. 2 it is indicated in dotted line that its front end is open in order to receive said catch or projection 76. 77 is a clearing in the front end of the receiver for the hook 75 of the extractor to pass into and reach the regular notch (not shown) in the end of the barrel and get a hold of the cartridge.

The hammer is raised by the pressure against its front side or projection 54^x of the square rear end 78 of the hammer-lifter 79, (shown in Figs. 5, 6, and 8,) which is of almost semicylindrical shape with a diagonal front cam edge 80, of which the rearmost end 40 terminates in the notch 81 and the front end in the squared-off point 82. 83 is a catch projecting from the under side of the hammer-lifter and serves to prevent the latter from dropping out accidentally when the breech-bolt is removed. This hammer-lifter is located in the recess 84, (best shown in the plan view, Fig. 4,) milled out for it in the receiver, so that its upper or inner curved face fits the lower face of the breech-bolt. When the 45 hammer-lifter is inserted into said recess, the catch 83 on its bottom is slipped down into the deeper recess 85. Said recesses run diagonally and parallel with the front edge 80 of the hammer-lifter, which bears against the front terminus 86 of the recess 84. When the parts are put together and the breech-bolt is pushed forward, the hammer-lifter fills the space between the shoulders 89 and 90 in Figs. 19 and 20, so that it is bound to 50 rock with the breech-bolt and thus be moved forward by the diagonal recess and leave the hammer free to work when the breech-bolt is turned to the right and interlocked and at no other time, and by raising the arm 42, 55 preparatory to pulling the breech-bolt back, the hammer-lifter is, by the coaction of the diagonal cam edges 80 and 86, forced rear-

wardly against the hammer, which is thereby raised to its full limit. When the breech-bolt is pulled back, the hammer-lifter is prevented from turning by having its notch 81 held by the hammer forward against the projection 91, adjacent thereto in the recess 84 in the receiver. When the breech-bolt is again moved forward and turned to the right, the 75 hammer-lifter turns with it and releases the hammer, which after losing the support of the lifter depends on the trigger to hold it up, and is thus ready to strike when the trigger is pulled. 80

92 is the opening in the receiver through which the empty cartridges are ejected, and 93 is the slot in rear thereof in which the extractor-bar 71 guidingly slides back and forth.

In the above description the operation of 85 the gun is already fairly explained. It may, however, be further stated that when the magazine is filled with cartridges and the cartridge cut-off is turned so as to allow the cartridges to enter the receiver the operator simply takes hold of the arm 42, raises it up, and pulls it back so that the cartridge can slip partly sidewise into the receiver. He then pushes the breech-bolt forward and locks it by turning it to the right, then pulls the trigger, and after thus firing one shot he repeats the operation with the breech-bolt and the trigger just as fast as he wishes and is able to, and everything works automatically until the magazine is empty, when he refills it 100 in the way above described. In pulling the breech-bolt back quickly the empty cartridge, which follows the hook 75 of the extractor, is thrown out of the receiver by the ejector 45, as already described, and when the breech-bolt is moved forward its right front edge adjacent to the mouth 19 of the magazine takes hold of the edge of the rear end of the cartridge and moves it forward, while the next cartridge or the cartridge-carrier itself urges 105 it inward until it is freed from the retaining-lip 96 and assumes a central position with and is pushed toward the center of the receiver. The inclined plane or shoulder 97 at the rear end of the receiver serves to guide 110 the arm 42 quickly into its locked position, and in raising the arm 42 said shoulder gives the breech-bolt and extractor a very powerful start rearwardly, thereby starting the empty cartridge, which sometimes from the 115 force of the shot is slightly swelled out and has a tendency to stick in the barrel.

The parts of the gun which ordinarily need cleaning may be taken apart and put together without tools of any kind whatsoever in the 125 following manner: Pull the breech-bolt back, with the front end of the extractor sprung upward, so that its projection 76 passes above the receiver. After thus removing the breech-bolt and extractor the latter may be separated 130 from the former by moving its tooth 73 along and out of the groove 74, then moving it rearwardly out, off the projection 67 of the breech-bolt. This will give access to the breech and

the receiver. The cartridge cut-off may be removed by raising its thumb-piece 34 upward and pulling it out against the frictional resistance of the spring-hook 39 40. The part 5 11 12 is simply to be pulled downward, and the lid 16 may then be pushed out to the left. The cartridge-carrier may next be swung out of the notch 24 and dropped down from its stud 22. The carrier-spring, being fastened 10 as shown, may also be dropped from its place when not held by the carrier. The pivots in the trigger and hammer may be pushed out, as they are not screw-threaded. The trigger-spring may be permanently fixed in the rear 15 end of the receiver and the main or hammer spring, being held in the manner shown, may be removed and reinserted without tools. There is not a single screw in the entire mechanism. The only three screws (98, 99, and 20 100) in the entire gun are for securing the stock or woodwork to the iron. To assemble or put the parts together, the proceeding is exactly the reverse of that just described for taking it apart.

25 From the above description it will be seen that I provide a gun which may be fired very rapidly, and it may have its magazine re-filled in a moment and its parts made strong, durable, few, and easy to take apart for cleaning, all of which points are very important, especially in guns used by the army, where sand and dust will often be apt to get into the mechanism, requiring frequent removal and cleaning of the working parts most exposed 30 to such incidents, and that for such cleaning of ordinary guns a box of tools is required, and the many small parts and still smaller screws are very apt to get lost, all of which difficulties I overcome in my invention.

40 The front locking-notch 49 for the bolt-lug 47 may extend to the top of the receiver, as in Fig. 10, and the stock need not necessarily extend underneath the magazine, but may have a clearing there to admit of the removal 45 of the bottom of the magazine, if so desired; but usually the magazine will need no cleaning, so I mention it more in order to show that even the magazine may be taken apart without tools or removal of the stock, as a 50 spring-catch may hold its bottom and permit it to be removed by applying suitable force or by pressing on a locking-spring.

Having thus described my invention, what I claim, and desire to secure by Letters Patent, is—

55 1. In a magazine bolt-gun, the combination with a receiver and a breech-bolt moving back and forth therein; of a magazine communicating therewith and forming a part of a cylinder around the receiver and having a lid or cover for admitting the cartridges to be dropped sidewise down into the magazine without changing the position of the gun and a spring-actuated cartridge-carrier adapted 60 to feed the cartridges into the receiver, said cover consisting of a curved plate sliding with its ends in suitably-provided curved grooves

and which presses the carrier back and locks it so it offers no resistance to the filling of the magazine, and when the cover is closed the 70 carrier is set free to chase all the cartridges toward the inlet to the receiver, said cover having also a projection by which it is easily operated, substantially as and for the purposes set forth.

75 2. In a firearm, the combination with a receiver having a cylindrical inside provided with a side inlet and top exit for cartridges, the gap 93, extending rearwardly from said top exit to the rear end of the receiver, the 80 notches 43^X, 49 and 50 formed in the upper wall of the receiver; the round breech-bolt 21 adapted to slide in the receiver and having the lugs 47, 48, and the arm 42, adapted to interlock with said notches, said breech-bolt 85 having further the circular groove 74, and the rear central projection 67; the flexible extractor-bar 71, sliding in the gap 93, and being provided at its front end with a hook for extracting the empty cartridges from the rear 90 end of the gun-barrel, and having its rear end extended across the rear end of the breech-bolt, and journaled upon the projection 67 thereof, also having the tooth or hook 73, engaging the circular groove 74 in the front side 95 of a semicircular projection near the rear end of the breech-bolt and means for ejecting the shells of the cartridges from the receiver, substantially as and for the purposes set forth.

100 3. In a firearm, the combination with the round breech-bolt 21, adapted to be rocked from side to side, in the receiver for interlocking or releasing it, and having an axial hole through it, and its rear end formed with a hollow cylindrical extension 67, with cams 105 or teeth in its bottom; the firing-pin 62, having a round body extending through the central hole in the bolt and having the rigid collar 65, inserted in the cavity 66 of the cylindrical extension of the breech-bolt, and provided with teeth or cams upon its front side 110 corresponding to those in the bottom of the cavity, and the rearwardly-extending four-cornered end 64; the cartridge-extractor 71, journaled to the rear end of the breech-bolt 115 and having the angular portion 70, with a square hole in it fitting the end 64, of the firing-pin to prevent it from turning with the bolt, said extractor being guidingly inserted in a gap in the receiver, permitting it to 120 slide but not to oscillate, substantially as and for the purpose set forth.

125 4. In a firearm, the combination with the receiver 4, 5, 6, the round breech-bolt 21, inserted in the receiver and having the operating-lever 42, with the segmental notch, and the firing-pin 62, extending through it, and beyond its rear end, said bolt being adapted to slide and oscillate so as to lock and unlock itself with the receiver; said receiver 130 having the diagonal or spiral-shaped recesses 84 85; the transversely-curved hammer-lifter 79, adapted to fit and retain itself in said grooves with its front and rear edges, and be-

tween the shoulders 89 and 90 of the breech-bolt with its side edges, it also having the square rear edge 78, for cocking the hammer of the gun; the hammer 54, mounted at the rear of the receiver adjacent to the rear edge of the hammer-lifter, and means for keeping the hammer-lifter in position when the breech-bolt is retracted, and means for driving and for releasing the hammer, substantially as shown, and described, and for the purpose set forth.

5. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the lid 16, for closing said outwardly-opening mouth, said lid consisting of a curved plate having its ends sliding in suitably-provided grooves and its upper edge formed into an out and upwardly projecting wing by which the lid is operated and the cartridges quickly guided into the magazine substantially as and for the purpose set forth.

6. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said outwardly-opening mouth; said magazine having the end walls 8 and 9 projecting transversely out from the receiver, and provided with the curved grooves 17 for the ends of said sliding lid to slide in, substantially as and for the purpose set forth.

45. 7. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said outwardly-opening mouth; said magazine having the end walls 8 and 9 projecting transversely out from the receiver, and provided with the curved grooves 17 for the ends of said rolling lid to slide in; the flat downwardly-sliding lid 12, closing the opposite side of the magazine, and having the segmentally-curved extension 11, overlapping the lower part of the sliding lid 16, and forming the bottom of the magazine, substantially as and for the purpose set forth.

65. 8. In a magazine bolt-gun, the combination with the receiver 4 5 and the breech-bolt mov-

ing therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said outwardly-opening mouth; said magazine having the end walls 8 and 9 projecting transversely out from the receiver, and provided with the curved grooves 17 for the ends of said lid to slide in; the flat downwardly-sliding lid 12, closing the opposite side of the magazine, and having the segmentally-curved extension 11, overlapping the lower part of the sliding lid 16, and forming the bottom of the magazine; the front end wall of the magazine having the horizontal slot or notch 24 opening toward the sliding lid 12, the pendent stem 22 at the lower side of the receiver forward of the magazine, the cartridge-carrier 23, 26 95 having its arm 23 pivotally placed upon said stud 22, and retained thereon by the said notch 24, in which it swings, and by the flexible arm 26 and head 95, and the auxiliary spring 27, empties the magazine into the receiver, substantially as shown and described.

9. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said outwardly-opening mouth; said lid being provided at its lower front corner with the locking-notch 31, the spring-pressed cartridge-carrier 23, 26 95, pivotally secured to the receiver in front of and extending into and swinging in the magazine and having the tooth 25 operated by the lower edge of the lid and engaging the locking-notch 31 of the lid when the latter is open, substantially as and for the purpose set forth.

10. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said outwardly-opening mouth; said lid being provided at its lower front corner with the clearing-notch 30 and the locking-notch 31; the spring-pressed cartridge-carrier 23 26 95 pivotally secured to the receiver, but extending through a slot into and swinging in the magazine, is provided with the tooth or lug 25 operated by the lower edge of the lid and engaging

the locking-notch 31, when the lid is open and finding a clearing in the notch 30 when the lid is either in motion or closed, substantially as and for the purpose set forth.

- 5 11. In a magazine bolt-gun, the combination with the receiver 4 5 and the breech-bolt moving therein, of a segmental horizontal magazine extending underneath and up along one side of the receiver, the said upwardly-extending portion being provided near its top with an inwardly-opening mouth communicating with the receiver and an outwardly-opening mouth for receiving the cartridges, and the curved, sliding lid 16, for closing said 15 outwardly-opening mouth; the cartridge-carrier arm 23, pivoted to the receiver and extending through a slot or notch in the end wall of the magazine, and formed with the upwardly-tending spring-arm 26, provided at 20 its free end with a head 95, either side of which is adapted to touch and move the cartridges sidewise and upward in the magazine, the auxiliary spring 27, pressing against the arm of the carrier so as to assist it in its horizontal movement; means for locking the carrier and lid when opened; and a suitable cut-off at the mouth or port extending from the magazine into the receiver, substantially as and for the purpose set forth.
- 25 12. In a magazine bolt-gun, the combination with a receiver and a magazine embracing a portion of the receiver and having a gate for the cartridges to enter sidewise into

the receiver, of a cartridge cut-off consisting of a rock-shaft provided with a rocker-arm 35 and having a half-round portion rocking in a groove in one side of the gate, the spring-arm 39, inserted in a groove in the rock-shaft and having its free end curved outward and engaging the transverse groove 41, in the receiver, substantially as and for the purpose set forth.

13. In a magazine bolt-gun the combination with a receiver and a magazine embracing a portion of the receiver and having a 45 gate for the cartridges to enter sidewise into the receiver, of a cartridge cut-off consisting of a rock-shaft provided with a rocker-arm and having a half-round portion rocking in a groove in one side of the gate, the spring- 50 arm 39, inserted in a groove in the rock-shaft and having its free end curved outward and engaging the transverse groove 41, in the receiver; the rear end of said rock-shaft extending beyond the rocker-arm and is journaled in the bearing 37, having the slot or notch 38, for the rocker-arm to pass through in removing or replacing the rock-shaft, substantially as shown and described.

In testimony whereof I affix my signature 60 in presence of two witnesses.

GUNERIUS SCIIOU.
